FABRIC CONTACTING CIRCUIT CLOSER FOR
KNITTING MACHINES

Michael Wachsman, Brooklyn, N. Y.

Application October 9, 1937, Serial No. 168,147

5 Claims. (Cl. 66—166)

This invention relates to improvements in circuit closers for knitting machines and has particular reference to a device for closing an electrical stop circuit by means of a fabric contacting detector. The object of the invention is to provide a circuit closing device including a fabric contacting detector for closing an electric circuit to actuate a knitting machine stopping device when a tear, a run, a dropped stitch or other irregularity or abnormal condition appears or occurs in the knitted fabric.

The invention is embodied in a fabric contacting circuit closing mechanism arranged and constructed as hereinafter set forth and as illustrated in the accompanying drawings in which

Fig. 1 is a side view of a contacting detector according to the invention.

Fig. 2 is an edge view thereof including a spacing collar.

Fig. 3 is a contacting detector including a plurality of elements.

Fig. 4 is an edge view thereof.

Fig. 5 is a view of the contacting head of the detector provided with a yielding contacting pin.

Fig. 6 is a detail view of a detector provided with an adjustable weight.

Figs. 7 and 8 are detail views of detachable detectors.

Fig. 9 is a view illustrating the use of the detectors on a knitting machine with rotary needle cylinder.

Fig. 10 is a detail view of the contact ring used in Fig. 9.

Fig. 11 is a view showing the use of the contactor illustrated in Fig. 3 on a knitting machine having a stationary needle cylinder.

Fig. 12 is a detail view showing the use of a single detector on a knitting machine having a rotary needle cylinder.

Fig. 13 is a view illustrating the use of a plurality of single detectors on a knitting machine having a stationary needle cylinder.

Fig. 14 is a detail view showing the use of a plurality of detectors according to Fig. 3 on a knitting machine having a stationary needle cylinder.

Fig. 15 illustrates a particular type of detector.

Fig. 16 is a fragmentary view of the contact ring used in Fig. 13.

Fig. 17 is a diagrammatic view illustrating the use of the contacting detectors with relation to the knitting needles.

The circuit closing mechanism according to this invention is adapted for use with any type of knitting machine. Hence no specific type of

machine is illustrated but the knitting mechanism as an element in this disclosure is identified diagrammatically by the rectangle 10 by means of which mechanism the yarns 11 are knitted together into a cylindrical fabric 12 which moves downward from the knitting mechanism in the direction of the arrows and which may be rotating as in Fig. 9, or non-rotating as in Figs. 11, 13 and 14.

The detector element according to this invention is in the form of a thin flat lever or arm which may conveniently be stamped out of sheet metal. The detector is adapted to be used edge-wise against the fabric to detect runs, dropped stitches, holes, tears and other abnormal conditions and to operate to close an electric stop circuit to stop the knitting machine so that the trouble may be attended to and waste eliminated or poor knitting detected.

Figs. 1 and 2 illustrate a single detector which includes a hub 15 from which extends a lever 16 ending in a contacting head 17. Diametrically opposite to the lever 16 there is a circuit closing finger 18. When the detectors are used side by side as hereinafter explained they are mounted in spaced relation by means of thin collars 19. A number of such detectors may be combined into a detector element. Thus Figs. 3 and 4 illustrate a detector element comprising a hub 15 from which four detector levers 20 extend crosswise. Each lever 20 ends in a contacting head 17 the heads being of different sizes and shapes as will be explained hereinafter. The detector element in Fig. 3 has no special circuit closing finger, one of the levers 20 being used for this purpose.

When the detectors are used for certain fine fabrics or for other reasons it may be desirable to provide a yielding contacting element. Fig. 5 illustrates a construction by way of example in which there is mounted a pin 22 in yielding slidable relation to the detector head 17. The pin is supported in upstanding lugs 23 and a spring urges the pin outward in an obvious manner. Inasmuch as the lever 16 in Fig. 5 is unbalanced, sliding weights 24 such as shown in Fig. 6 may be used to balance the detector element. Figs. 7 and 8 illustrate an element in which the detector levers are detachable from the hub. In these figures the hub of the element is marked 25 and has a supporting finger 26 extending to one side. The detector lever 27 is laid against the finger 26 and a sleeve 28 is slid down over the two elements. The lever 27 is pushed down until it comes to rest upon the

shaft 38 upon which the detectors are mounted when in use.

Fig. 9 illustrates the use of a plurality of detectors 16 on a knitting machine having a rotary needle cylinder as indicated by the arrow 38. In use there will be a detector for each wale of stitches in the fabric. This arrangement is diagrammatically indicated in Fig. 17 in which the wales of stitches in the fabric are indicated 5 at 31 as produced by the needles 32 of whatever type of knitting mechanism is used. Opposite each wale of stitches there is mounted a detector element for instance the element 16 as hereinafter described. When a stitch is dropped or other abnormal condition occurs in the fabric, the detector head moves inwardly and causes the electric circuit to be closed.

In Fig. 9 the reference numeral 35 indicates a ring formed shaft within which the fabric passes 20 downward from the knitting mechanism in the usual manner while the entire assembly rotates. Upon the shaft 35 there is mounted as many detectors 16 as there are wales in the fabric or needles used, the detectors extending inwardly 25 from the shaft like the spokes in a wheel. The detector heads 17 rest by gravity against the fabric. If desired weights such as 24 may be used or springs, not shown, to increase the friction 30 between the detector heads and the fabric in an obvious manner. The shaft 35 is mounted to rotate with the knitting mechanism 10 by means of any suitable framework 36 which also carries a contacting ring 37. The circuit closing fingers 18 of the detectors are adapted to contact a contact ring 38 to close the circuit. The ring 38 is supported stationarily by one or more suitable supports 39. A contact spring 40 is mounted on the support 39 and engages the rotating contact ring 37. The terminal wires 41 and 42 of the 40 electric stop circuit are connected to the contact ring 38 and the contact 40.

If during the operation of the machine an abnormal condition occurs in the fabric whereby the resistance of the fabric to the inward pressure 45 of a detector head is removed or lessened, such detector head will move inward, being gravity actuated, the contact finger 18 will move outward and close the electric circuit by contact with the ring 38. The latter may have an uneven lower 50 surface as indicated at 43 in Fig. 10 to insure clean wiping contact between the finger 18 and the ring.

The detectors 16 may be used on a knitting machine having a stationary needle cylinder in the 55 manner shown in Fig. 13 in which the detectors are mounted like the spokes in a wheel on a stationary ring formed shaft 35 secured by suitable supports 44. The latter may also support the contact ring 45. In this figure the electric circuit is shown complete including a battery 46 and an electromagnet 47 which operates the stopping lever or other element 48 of the usual stop mechanism, not shown, to stop the machine in a well known manner. The contact ring 45 may have 60 slits 49 to be engaged by the contact fingers 18 for good clean contact Fig. 16.

The detectors 16 will be mounted at any suitable elevation with relation to the knitting mechanism. It may not always be possible to mount 70 the detectors as close to the knitting mechanism as is usually desirable in order to detect abnormal conditions as close to the needles as possible. Or again, it may be desirable to employ special means to detect special types of tears or holes in 75 the fabric close to the needles in addition to the

employment of the detectors 16 as arranged in ring-formed relation to the fabric. It may therefore at times be necessary to employ one or more extra long detectors such as shown in Fig. 15 in which a long detector 50 is mounted on the 5 shaft 35 so as to reach up under the knitting mechanism.

Fig. 11 illustrates the use of a single detector element according to Fig. 3. The element is mounted on a shaft 52 and a detector lever is urged into frictional engagement with the fabric by a spring 53. A weight 24 may of course be used on the lowermost lever 20 for the same purpose. A support 54 supports the shaft 52 and a suitable contact finger 55. When the fabric at the line of contact with the detector head 17 collapses or becomes less in circumference due to a hole or tear, or when such a hole or tear comes opposite the head 17, the detector will move inward and its lowermost lever 20 will engage the contact finger 55 to close the circuit. The detector element according to Figs. 3 and 11 possesses the advantage that by simple rotation a suitable detector head may quickly be brought into operative position with relation to the fabric. A simple turning aside of the spring 53 and the contact finger 55 will permit of such change. The detector heads are differently shaped and dimensioned to suit the fabric operated upon. The fabric may for instance be 30 knitted with a design which includes open work or openings. In such case the largest detector head will be turned into engagement with the fabric to bridge such holes so that the detector will not be actuated to close the circuit when such an intended opening comes opposite the 35 detector head.

Detectors with a plurality of levers 20 may also be used in the manner described in connection with Fig. 13. Such use is illustrated in Fig. 14 in which a number of detector elements with levers 20 are mounted side by side on a ring formed shaft 60. The latter is carried by one or more supports 61. A contact ring 62 similar to the contact ring 45 is supported by arms 63 adjustably secured to the supports 61 by thumb screws 64 for instance. A spring 65, one for each detector element, is attached between the latter and the arm 63 and urges the detector head into contact with the fabric in an obvious manner. When the contacting detector head moves inward due to an abnormal condition in the fabric another lever 20 engages the contact ring to close the circuit as will be understood. When it is desired to swing another lever 20 into operating position, the 55 spring is detached, the thumb screw 64 loosened and the ring 62 lowered. Then the desired change is made and the parts moved back into position to operate. It will be noted that any of the elements 20 may be changed, without affecting the 60 other elements on the shaft 60.

If it should be desired to employ a single detector close to a knitting machine having a rotary needle cylinder a construction such as shown in Fig. 12 may be used. The detector 16 is here 65 mounted upon a vertical shaft 70 to move laterally in the direction of the arrow 71 against the direction of movement of the fabric as indicated by the arrow 72. A spring 73 urges the lever into 70 operative relation with the fabric. The contact finger 18 will close the circuit which is indicated by the two terminal contacts 74. These may be mounted by any convenient means, not shown. If a tear occurs in the fabric the detector will 75

swing inward, the circuit will be closed and the machine stopped.

The fabric contacting circuit closers for knitting machines according to this invention may be used singly or in as great a number as may be necessary to detect abnormal conditions in the fabric at any point thereof. They may be used with stationary or rotary needle cylinders and may be combined in any desired combinations some of which are shown in the drawings. These latter are illustrative only and I do not desire to limit myself to the exact disclosures herein otherwise than as is determined by the legitimate and intended scope of the appended claims.

15 I claim:

1. A fabric contacting circuit closer for knitting machines in which the knitted fabric has a movement away from the knitting mechanism comprising a ring formed shaft, a plurality of 20 contact fingers on said shaft, said fingers being held by gravity in normal frictional contact with the fabric, there being a contact finger for each wale of stitches in the fabric, means supporting said shaft stationary relative to the movement of 25 the fabric, a normally open electric stop circuit for the knitting machine and means operated by the contact fingers to close the said electric circuit to stop the knitting machine when an abnormal condition in the moving fabric causes a 30 termination of the normal frictional contact between the contact fingers and the fabric.

2. A fabric contacting circuit closer for knitting machines having rotary needle cylinders in which the knitted fabric has a movement away from the 35 needle cylinder and rotates therewith comprising a shaft, a plurality of contact fingers on said shaft in gravity actuated normal frictional contact with the fabric, there being a contact finger for each wale of stitches in the fabric, means 40 supporting said shaft to rotate with the needle cylinder and the fabric and stationary relative to the movement of the fabric away from the needle cylinder, a normally open electric stop circuit for the knitting machine and means operated by the 45 contact fingers to close said circuit to stop the knitting machine when an abnormal condition in the moving fabric causes any one of said contact fingers to move away from its said normal frictional contact with the fabric.

50 3. A circuit closing mechanism for knitting

machines comprising a ring formed shaft surrounding the knitted fabric as it comes from the knitting mechanism of said machine, a plurality of fabric contacting detectors on said shaft extending inwardly from the same in normal contact with the fabric under the influence of gravity, a contact ring, a normally open electric stop circuit for the knitting machine including said contact ring and detectors and a contact finger on each detector for engaging said contact ring to 10 close the said circuit when any one of said detectors is moved into a circuit closing position because of a termination of said normal contact position between any one detector and the fabric.

4. A circuit closing mechanism for rotary needle cylinder knitting machines comprising a ring formed shaft surrounding the knitted fabric as it comes from the needle cylinder of the machine, a plurality of gravity actuated detectors on said shaft in normal contact with the said fabric, 20 means connecting said shaft to rotate with the needle cylinder, a stationary contact ring, a normally open electric stop circuit for the knitting machine including said contact ring and detectors and a contact finger on each detector for engag- 25 ing said contact ring to close the said circuit when any one of said detectors is moved into a circuit closing position because of a termination of said normal contact position between any one detector and the fabric.

30 5. A circuit closing mechanism for knitting machines comprising a ring formed shaft surrounding the knitted fabric as it comes from the knitting mechanism of the machine, a plurality of detector elements on said shaft extending inwardly therefrom, each of said detector elements including a plurality of detector levers, means for keeping any one of said levers in normal frictional contact with the fabric, a contact ring, a normally open electric stop circuit for the knitting 40 machine including said contact ring and the said detector elements, one of said detector levers in each of said detector elements serving to engage said contact ring to close the said stop circuit when any one of the said detector levers is moved 45 into a circuit closing position because of a termination of said normal contact between the fabric and the said detector lever.

MICHAEL WACHSMAN. 50
